Des. 212,517
Patented Oct. 22, 1968

212,517

COMBINED MIRROR AND LIPSTICK HOLDER

Mortimer J. Harrison, Santurce, Puerto Rico, assignor to Bishop Industries Inc., Union, N.J., a corporation of
New York

Filed Nov. 24, 1967, Ser. No. 9,526

Term of patent 14 years

(Cl. D86—10)

Fig. 1

Fig. 2

Fig. 3

Fig. 4

Fig. 5

Fig. 6

FIG. 1 is a perspective view showing the front side of a lipstick holder and mirror embodying the new design;

FIG. 2 is a front elevational view of the lipstick holder and mirror of FIG. 1;

FIG. 3 is a top plan view of the lipstick holder and mirror of FIG. 1;

FIG. 4 is a rear elevational view of the lipstick holder and mirror of FIG. 1;

FIG. 5 is a side elevational view of the lipstick holder and mirror of FIG. 1; and

FIG. 6 is a bottom plan view of the side shown in FIG. 5.

I claim:

The ornamental design for a combined mirror and lipstick holder, substantially as shown and described.
